PUMPING APPARATUS

Ralph E. Lamberton, Michigan City, Ind., assignor to Sullivan Machinery Company, a corporation of Massachusetts

Application November 27, 1934, Serial No. 755,014

13 Claims. (Cl. 230—26)

My invention relates to pumping apparatus for compressible fluids, and, from another aspect, to improved unloading means for such pumping apparatus.

When a multi-stage compressor is provided with a total closure intake unloader for the low pressure cylinder and unloads the high pressure cylinder by opening and maintaining open the inlet valves of the latter, there is a tendency for the intercooler pressure gradually to build up, due to leakage past the intake unloader valve and absence of removal of air from the intercooler by the high pressure cylinder; and therefore there is a periodic popping of the safety valve which is provided on the intercooler, which is annoying and at times undesirable. If, however, means can be provided for venting the intercooler at such a rate that a moderate pressure may still be maintained therein, while avoiding the building up of an excessive pressure, this would be desirable; and from one aspect my invention consists in the provision of improved means for accomplishing this function.

An object of my invention is to provide an improved pumping apparatus. Another object of my invention is to provide an improved multi-stage pumping apparatus having improved unloading means. Still another object of my invention is to provide an improved arrangement for maintaining intercooler pressure within desired limits during the unloaded operation of a multi-stage compressor. Yet another object of my invention is to provide an improved automatically-controlled relief valve system for multi-stage compressor intercoolers. Other objects and advantages of the invention will hereinafter more fully appear.

In the accompanying drawing:

Fig. 1 is a side elevational view of a multi-stage compressor arranged in accordance with the illustrative embodiment of my invention;

Fig. 2 is a vertical section taken on line 2—2 of Fig. 1;

Fig. 3 is a fragmentary sectional view through a portion of a high pressure cylinder unloading means; and

Fig. 4 is a horizontal section showing details of construction of the intake type unloader casting.

From the drawing it will be noted that the compound compressor 1 shown has a frame 2, a drive shaft 3, a flywheel 4 driven by suitable driving connections, including herein a belt 5 of which a portion only is shown, the crankshaft 3 serving 55 to actuate the pistons (not shown) in the low

pressure cylinder 6 and in the high pressure cylinder 7. The low pressure cylinder 6 discharges through a connection 8 to an intercooler 9 provided with a suitable pop valve 10; and from the intercooler the cooled and partially compressed fluid passes through a connection 11 to the high pressure cylinder 7, after a further compression in which it is discharged through a discharge line 12 to any suitable point of use. The low pressure cylinder 6 receives air through a connection 13 opening out of an intake closure unloader valve casing 14, the latter having spaces 15 and 16 connected through an air cleaner 17 to the atmosphere, and a central chamber 18 communicating through the opening 13 with the inlet space of the low pressure cylinder. Webs 19 and 20 separate the chamber 18 from the chambers 16 and 15 respectively, and a double-beat valve 21 having a portion 22 adapted to close the opening through the web 19 and a portion 23 adapted to close the opening through the web 20 is reciprocable in the casing 14. Valve 21 is normally held in open position by a spring 24 acting upon its lower end, and may be moved to closed position by a plunger 25 reciprocable in a cylinder 26 and adapted to be supplied with air through a connection 27 under the control of a pilot valve 28 supplied with pressure from the high pressure discharge line 12 through a connection 29. When the pressure in the compressor discharge line 12 reaches a predetermined desired maximum, the pilot valve 28 operates in a well-known manner to supply fluid through the line 29 and the connection 27 to the space above the piston 25, and thereby the latter is caused to force the valve 21 to closed position. Another connection 30 branches off the line 27 and leads to plungers 31 which are adapted to open and maintain open the inlet valves 32 of the high pressure cylinder. Accordingly, it will be noted that when the pilot valve 28 supplies pressure to the line 27 to effect closure of the intake closure valve for the low pressure cylinder, the high pressure cylinder ceases to act as a pump, due to the maintaining open of its inlet valves 32, and is also unloaded, and accordingly there will be no fluid discharged from the intercooler 9 by the high pressure cylinder 7; and indeed, should the discharge valves of the high pressure cylinder prove at all leaky, there may be some return of air from the line 12 to the intercooler. Moreover, in the event that air leaks past the valve 21 this will be compressed in the low pressure cylinder 6 and discharged to the intercooler, and therefore the pressure in the latter

may build up sufficiently to open the pop valve, with undesirable noise and with some waste of power, and undesirable heating due to the compression of the air to a higher pressure than is desired in the intercooler.

To avoid the difficulties mentioned I have provided in alignment with the cylinder 26 and mounted within a cover 34 for that cylinder, an automatic arrangement for venting, as desired, 10 the intercooler. The head 34 contains a pair of aligned cylindrical chambers 35 and 36 connected by a passage of reduced cross-section 37 whose opposite ends are surrounded by conical seats respectively numbered 38 and 39. The central 15 passage 37 is communicable through a lateral passage 40 controlled by an adjustable needle valve 41 with a passage 42 which opens into the space 16 within the intake closure valve casing 14, and accordingly any noise from air flowing out 20 ward through the passage 42 will be muffled by the air cleaner 17. Within the chambers 35 and 36 there are arranged respectively an end seating 25 valve 44 and a plunger 45, each of which has a stem extending towards the other, which stems are respectively numbered 46 and 47, and which 30 are of such length that the valve and plunger, each of which is beveled to cooperate with one of the conical seats, can not both seat at the same time. A spring 48 normally maintains valve 44 seated and plunger 45 off of seat 39. The valve 44 is provided with a longitudinal groove 53 so that when it is unseated fluid may flow longitudinally along it. The chamber 49 above the valve 44 is connected by a connection 50 with any suitable 35 point between the low pressure cylinder discharge valves and the high pressure cylinder inlet valves, herein to the discharge line 8 from the low pressure cylinder. A passage 51 formed in a threaded plug 52 which limits the downward 40 movement of the plunger 45, subjects the lower end of the latter continuously to the pressure conditions to which the piston 25 is subjected. Accordingly whenever fluid is supplied to depress the piston 25, fluid also flows through the passage 51 45 to raise the plunger 45, and because the pressure below the plunger 45 is higher than the pressure above the valve 44, the latter is unseated, and communication is established between passage 50 and passage 42. The valve 41 is preferably adjusted in such manner as to maintain a pressure 50 in the intercooler suited to the design of the compressor, the pressure ranging from 30 lbs. in compressors having a relatively low overall range of compression to considerably higher pressures as 55 the high pressure discharge pressure rises. Piston 25 and cylinder 26, and piston 45 and cylinder 36 will be noted to constitute aligned, reversely acting servo motors having communicating cylinders.

60 The mode of operation of the invention will be very readily understood from what has been already said. When the compressor discharge pressure rises to the desired maximum value, the pressure conducted through the line 29 and acting 65 upon the pilot mechanism 28 causes the latter to admit pressure simultaneously to close the valve 21 and to open the inlet valves 32. The compressor is therefore unloaded and while pressure might tend to build up in the intercooler due to 70 leakage, as previously explained, there will be no pressure discharged from the intercooler by the high pressure cylinder. The pressure in the intercooler will, however, be prevented from building up to too high a value, because as the plunger 75 25 closes the valve 21, the plunger 45 simultane-

ously will unseat the valve 44; and a leak connection will thus be opened from the line 8 which communicates with the interior of the intercooler, the air from the latter venting through the passage 50, chamber 49, through the groove 53, passage 37, lateral passage 40, past the needle valve 41, through the passage 42, into the space 16 and thus escaping to the atmosphere. The intercooler pressure will remain substantially whatever is fixed by the setting of the valve 41; and the setting of this valve will be determined, by observation, substantially merely to offset the rates of fluid supply into the intercooler by leakage back from the line 12, and due to leakage past the closed intake valve 21. When the compressor 15 is to be loaded again due to drop in discharge line pressure, the pressure above the piston 25 and below the piston 45 will be simultaneously vented; and the valve 44 will close the leak connection simultaneously with the opening of the intake 20 closure valve 21.

It will be evident that I have provided a very simple and effective arrangement for maintaining intercooler pressure at a desired value during normal unloaded operation of the compressor. 25 It will be obvious that the arrangement is capable of application to portable compressors as well as stationary compressors, and usable with any arrangement of unloading in which an intake is closed to a lower stage cylinder and discharge 30 from an intercooler is precluded by virtue of the type of the unloading apparatus used for the next higher pressure stage cylinder. The apparatus will be noted to be simple, effective, adjustable to different conditions and wholly automatic in 35 operation.

While I have in this application specifically described one form which my invention may assume in practice, it will be understood that this form of the same is shown for purposes of illustration, and that the invention may be modified and embodied 40 in various other forms without departing from its spirit or the scope of the appended claims.

What I claim as new and desire to secure by Letters Patent is:

1. In combination, a multi-stage compressor having an intercooler, an intake closure type unloader for the low pressure cylinder, an unloading apparatus for the high pressure cylinder effective to interrupt the discharge of pressure from the intercooler by said high pressure cylinder, and means for simultaneously providing a controlled venting of the intercooler pressure. 50

2. In combination, a multi-stage compressor having an intercooler, an intake closure type unloader for the low pressure cylinder, an unloading apparatus for the high pressure cylinder effective to interrupt the discharge of pressure from the intercooler by said high pressure cylinder, and means governed by compressor discharge pressure for effecting operation of said unloading means, and means also governed by compressor discharge pressure for simultaneously providing a controlled venting of the intercooler pressure. 60

3. In combination, a multi-stage compressor having an intercooler, an intake closure type unloader for the low pressure cylinder, an unloading apparatus for the high pressure cylinder effective to interrupt the discharge of pressure from the intercooler by said high pressure cylinder, and means governed by compressor discharge pressure for effecting operation of said unloading means, and means also governed by compressor discharge pressure for simultaneously providing 70

75

76

- a controlled venting of the intercooler pressure, said last means and said intake closure type unloader each including a valve-actuating plunger, said plungers arranged coaxially.
5. In combination, a multi-stage compressor having an intercooler, an intake closure type unloader for the low pressure cylinder, an unloading apparatus for the high pressure cylinder effective to interrupt the discharge of pressure from the 10 intercooler by said high pressure cylinder, and means for effecting operation of said unloading means, and means for simultaneously providing a controlled venting of the intercooler pressure, said last means and a portion of said unloading equipment each including a valve actuating plunger, said plungers arranged coaxially. 15
5. In combination, a multi-stage compressor having an intercooler, an intake closure type unloader for the low pressure cylinder, an unloading apparatus for the high pressure cylinder effective to interrupt the discharge of pressure from the intercooler by said high pressure cylinder, means for effecting operation of said unloading means, and means for simultaneously providing a controlled venting of the intercooler pressure including a relief valve mounted upon said intake type unloader and opened when the latter is closed. 20
6. In combination, a multi-stage compressor having an intercooler, an intake closure type unloader for the low pressure cylinder, an unloading apparatus for the high pressure cylinder effective to interrupt the discharge of pressure from the intercooler by said high pressure cylinder, means for effecting operation of said unloading means, and means for simultaneously providing a controlled venting of the intercooler pressure including a relief valve mounted upon said intake type unloader and moving in the same direction 25 as the latter to effect closure. 40
7. In combination, in a multi-stage compressor, high and low pressure cylinders and an intercooler, an intake closure unloader for the low pressure cylinder including a servo motor cylinder and piston, means for interrupting pumping by the high pressure cylinder, and intercooler venting means including a second servo motor cylinder and piston coaxial with the first-mentioned servo motor cylinder and piston. 45
8. In combination, in a multi-stage compressor, high and low pressure cylinders and an intercooler, an intake closure unloader for the low pressure cylinder including a servo motor cylinder and piston, means for interrupting pumping by the high pressure cylinder, and intercooler venting means including a second servo motor cylinder and piston coaxial with the first-mentioned servo motor cylinder and piston, said servo motor cylinders freely communicating with each other. 55
9. In combination, a multi-stage compressor having high and low pressure cylinders and means connecting the discharge of the latter to the intake of the former, intake closure unloading means for the low pressure cylinder, unloading means for the high pressure cylinder interrupting when effective the pumping action thereof, and means for discharging fluid from said connecting means while said unloading means are effective at at least as low a pressure as normally prevails 10 in said connection during pumping. 5
10. In combination, a multi-stage compressor having high and low pressure cylinders and means connecting the discharge of the latter to the intake of the former, intake closure unloading means for the low pressure cylinder, unloading means for the high pressure cylinder interrupting when effective the pumping action thereof, and means actuated concurrently with said unloading means for discharging fluid from said 15 connecting means while said unloading means are effective. 20
11. In combination, a multi-stage compressor having high and low pressure cylinders and means connecting the discharge of the latter to the intake of the former, intake closure unloading means for the low pressure cylinder, unloading means for the high pressure cylinder interrupting when effective the pumping action 25 thereof, means for discharging fluid from said connecting means while said unloading means are effective, and common pilot means for said unloading and fluid discharging means. 30
12. In combination, a multi-stage compressor having high and low pressure cylinders and means connecting the discharge of the latter to the intake of the former, intake closure unloading means for the low pressure cylinder, unloading means for the high pressure cylinder interrupting when effective the pumping action thereof, 35 means for discharging fluid from said connecting means while said unloading means are effective, and common controlling means governed by compressor discharge pressure for said unloading and 40 fluid discharging means. 45
13. In combination, a multi-stage compressor having high and low pressure cylinders and means connecting the discharge of the latter to the intake of the former, intake closure unloading means for the low pressure cylinder, unloading means for the high pressure cylinder interrupting when effective pumping action thereof, means for discharging fluid from said connecting means during unloaded operation of the compressor, and a pilot valve responsive to compressor discharge 50 pressure controlling supply and venting of compressor discharge pressure to effect unloading and venting and interruption of venting and re-loading in accordance with compressor discharge 55 pressure variations. 60
